CLAIM

The ornamental design for a baby LED weaning cup, as shown and described.

DESCRIPTION

FIG. 1 is a front elevational view of a baby LED weaning cup showing my new design;

FIG. 2 is a top perspective view thereof;

FIG. 3 is a bottom perspective view thereof;

FIG. 4 is a bottom plan view thereof; and,

FIG. 5 is a top plan view thereof.

The back elevational view, left elevational view, and right elevational view are identical to the front elevational view.
